UNITED STATES PATENT OFFICE.

HANS C. BEHR, OF SAN FRANCISCO, CALIFORNIA, ASSIGNOR TO FRASER & CHALMERS, OF CHICAGO, ILLINOIS.

HOISTING APPARATUS.

SPECIFICATION forming part of Letters Patent No. 657,689, dated September 11, 1900.

Application filed May 2, 1899. Serial No. 715,297. (No model.)

To all whom it may concern:

Be it known that I, HANS C. BEHR, a citizen of the United States, residing in the city and county of San Francisco, in the State of California, have invented certain new and useful improvements in Hoisting Apparatus; and I do hereby declare that the following is a full, clear, and exact description thereof.

The present invention relates to certain new and useful improvements in hoisting machinery for use in connection with the working of mines or such where the hoisting rope or cable winds off and on one or more drums; and it consists more especially in certain improvements in the hoisting mechanism fully set forth and described in Letters Patent No. 627,769, granted to me on the 27th day of June, 1899, for improved hoisting machinery.

In my aforesaid Letters Patent No. 627,769 means are provided for relieving the sheaves and the hoisting-rope of the undue wear resulting by reason of the side or lateral deviation of the winding rope or cable as the same is wound off or on the hoisting drum or drums; but the devices therein described do not provide for relieving the carriage, upon which the drum-sheave is mounted, of the lateral strain incident to the pull of the cable or hoist rope.

The object of the present invention is to compensate, so to speak, for such lateral strains and so arrange that the pit-sheave and the drum-sheave will move or swing in unison with the lateral deviation of the hoist rope or cable in order to adjust their plane of rotation, so as to coincide with the deviation of the rope or cable between, while at the same time relieving the traveling carriage of the drum-sheave of undue friction due to the pull of the hoist rope or cable.

In order to comprehend the invention, reference should be had to the accompanying sheet of drawings, forming a part of this application, wherein—

Figure 1 is a side view in elevation. Fig. 2 is a top plan view of the mechanism illustrated in Fig. 1, and Fig. 3 is a detail front view of the swiveling mechanism for the pit-sheave.

In the drawings the letter A is used to indicate a suitable gallows-frame and A' the

pit-sheave arranged within or in close proximity to the gallows-frame. A short distance from said frame is located the winding or hoisting drum B, which is mounted upon suitable supports B', and above or in close proximity to this drum is arranged a traveling sheave B², which directs the rope or cable C to the drum B, said rope or cable being the hoisting rope or cable leading up from the shaft and over the pit-head sheave C' down to and over the sheaves A' and B². These parts are substantially the same in working and arrangement as the corresponding parts fully set forth and described in my former application, Serial No. 704,815. Hence detail description thereof is not deemed necessary in the present application.

For the purpose of relieving the carriage C², above which the sheave B² is mounted, of the lateral strain due to the pull of the rope or cable C the pit-sheave A' and traveling guide-sheave B² are mounted at opposite ends of the same girder-frame D, which acts as a strut to resist the pull of the rope between the sheaves. Close to the hoisting-drum this frame is traversed by suitable mechanism, so as to maintain the edge of the guide-sheave B² approximately in a fixed plane tangent to the winding side of the hoisting-drum, swinging at the same time about a point near its other end. For this purpose the girder-frame D is supported and swiveled at a at its lower end upon carriage or truck C², the carriage-truck being traversed on suitable rails b by means of the screw b' or other suitable mechanism. The screw b' is shown supported in bearings b², and the same is driven by the chain-gearing d' d² from the axis of the drum or any part rotating with the drum. This operating-screw engages the nut e at the side of the carriage or truck C². If the swiveling-point is not in line of the rope leading from the guide-sheave to the drum, but a little distance back of it, then the track or rails b on which the carriage or truck C² is traversed should be slightly curved, in order to keep the rope or cable leading edge of the guide-sheave at all positions in its travel strictly within the fixed plane tangent to the winding side or face of the drum B. In practice, however, the amount by which the rope

or cable leading edge of the guide-sheave is carried away from this fixed plane is so slight with a straight track that the latter gives in most cases a sufficiently-correct approximation to the mathematically-correct path of the sheave edge. The other end of the girder-frame opposite to that carrying the guide-sheave and supporting the pit-sheave A' is flexibly connected or hinged at a' to the links 10 D², which links are likewise hinged at their lower end to the swivel-pin D³ free to turn about a vertical axis. By thus pivotally connecting the upper end of the girder-frame to a swivel-pin by a connection capable of movement at right angles to the direction within which the truck or carriage C² moves with the laying off or on of the rope upon the hoist-drum the lateral swing of the guide-sheave and lower end of the girder-frame is compensated for at its upper end, or, in other words, the upper end of said girder-frame is permitted sufficient longitudinal movement so that the end near the drum will be able to follow the path prescribed by the track upon which 25 the truck C² is traversed.

While I have shown and described the sheave A' as a pit-sheave from which the rope or cable is led to a sheave C', acting as a pit-head sheave which leads the rope or cable to the pit, it is obvious that said sheave A' may serve as the pit-head sheave, as illustrated in Figs. 1 and 2 of the drawings contained in my former application, Serial No. 704,815, above referred to.

35 By connecting the upper and lower sheaves by a rigid structure pivotally mounted, so as to have movement at each end, the said sheaves will move or swing in unison with the travel or movement of carriage or truck C² and said carriage or truck be relieved of the undue friction to which it is subjected by the lateral strain due to the pull of the cable or rope where the sheaves are mounted to swing

independently of each other. The disposition and arrangement of the sheaves as thus 45 described prevent the vertical swinging and sagging of the hoisting-rope rubbing against the flanges of the sheaves, for the reason that the sheaves rotate in the same plane as the sag of the rope. 50

Having thus described my invention, what I claim as new, and desire to secure protection in by Letters Patent, is—

1. The combination with the winding-drum, of a truck or carriage arranged in close proximity thereto, a sheave-frame pivoted at each end, a rope-sheave mounted at each end of said frame, and of means whereby the carriage is caused to travel lengthwise of the winding-drum in order that the rope-leading 60 edge of the sheave mounted at such end of the frame shall move within a plane tangent to the winding face or side of the drum in correspondence with the laying on or off of the rope or cable. 65

2. The combination with the winding-drum, of the pit-sheave, a guide-sheave located a distance therefrom, a rigid connection between said sheaves, a longitudinally-movable device to which the upper end of the frame 70 is flexibly connected, a laterally-movable carriage to which the said frame is pivotally connected at its lower end, and of mechanism for causing the said carriage to traverse the winding-drum with the laying on or off of the rope 75 or cable so that the rope-leading edge of the guide-sheave mounted within the frame will move within a plane tangent to the winding-face of the drum.

In testimony whereof I hereunto affix my 80 signature, in presence of two witnesses, this 27th day of April, 1899.

HANS C. BEHR.
